United States Patent Office

Des. 219,490
Patented Dec. 15, 1970

219,490

ROUND PRODUCE TABLE

John A. Plessinger, 1725 Wesleyan Road,
Dayton, Ohio 45406

Filed Sept. 8, 1969, Ser. No. 19,054

Term of patent 14 years

Int. Cl. D6—01

U.S. Cl. D80—9

FIG-1

FIG-2

FIG-3

FIG. 1 is a perspective view of a round produce table embodying my new design.

FIG. 2 is a plan view of the round produce table illustrated in FIG. 1.

FIG. 3 is an elevational view of the round produce table illustrated in FIG. 1.

I claim:

The ornamental design for a round produce table, as shown.
